UNITED STATES PATENT OFFICE.

OLIVER H. MUNTZ, OF PITTSBURG, PENNSYLVANIA, ASSIGNOR OF ONE-HALF
TO JOHN W. CRIDER, OF CINCINNATI, OHIO.

DESIGN FOR A HARNESS D.

SPECIFICATION forming part of Design No. 31,938, dated December 5, 1899.

Application filed November 10, 1899. Serial No. 736,545. Term of patent 14 years.

To all whom it may concern:

Be it known that I, OLIVER H. MUNTZ, a citizen of the United States of America, residing at Pittsburg, in the county of Allegheny and State of Pennsylvania, have invented a certain new and useful Design for a Harness **D**, of which the following is a specification, reference being had therein to the accompanying drawings.

10 My invention relates to a certain new and useful design for harness **D**'s, and has for its object to provide a design of new and original shape.

15 As shown in the accompanying drawings, the **D** consists of the novel outline and configuration, which will be hereinafter more fully described and specifically pointed out.

20 In describing the invention in detail reference is had to the accompanying drawings, forming a part of this specification, and wherein like numerals of reference indicate corresponding parts throughout the several views, in which—

25 Figure 1 is a perspective view of my new and useful design for a harness **D**. Fig. 2 is a

front view of the same. Fig. 3 is a side elevation thereof.

In the drawings the reference-numerals 1 1' indicate the horizontal or longitudinal base portions, having their outer end bent at right angles thereto, as at 2 2', and the inner end bent vertically in a curvilinear manner, as at 3 3', both of these ends being brought in close proximity to one another. An oblong head 4, extending in alinement with the base portions, is formed integral with the curvilinear portions 3 3' and is provided with an opening 5, formed at the top of the **D**.

30 Having fully described my invention, what I claim as new, and desire to secure by Letters Patent, is—

35 The design for a harness **D**, as herein shown and described.

40 In testimony whereof I affix my signature in the presence of two witnesses.

OLIVER H. MUNTZ.

Witnesses:

JOHN NOLAND,
WILLIAM E. MINOR.
